UNITED STATES PATENT OFFICE.

CHARLES M. HAYNES, OF CHILlicothe, OHIO.

SELF-FILLING FOUNTAIN PEN.

Application filed November 29, 1921. Serial No. 518,541.

To all whom it may concern:

Be it known that I, CHARLES M. HAYNES, a citizen of the United States of America, residing at Chillicothe, in the county of 5 Ross and State of Ohio, have invented certain new and useful Improvements in Self-Filling Fountain Pens, of which the following is a full, clear, and exact description.

10 This invention relates to fountain pens of the type in which the filling of the pen with ink is effected by means of a reciprocating plunger or piston working in the barrel to draw the ink into the same by 15 suction, and its chief object is to provide an improved device of the kind indicated, in which with the exception of the piston the working parts are outside of the ink-space of the barrel, thereby increasing the ink 20 capacity of the pen. Another object is to provide a self-filling pen of the utmost simplicity and durability of construction, in which possibility of getting out of order is practically eliminated. To these and 25 other ends the invention consists in the novel features and combinations hereinafter described.

One form of the invention is illustrated in the accompanying drawing, in which— 30 Fig. 1 is a longitudinal section showing the pen ready for use, with the filling mechanism in the position occupied after the filling has been effected.

Fig. 2 is a longitudinal section showing 35 the piston advanced, for filling the barrel.

In the construction illustrated the piston 10 has a liquid tight fit in the barrel or ink reservoir 11, and to that end may be wrapped or covered with yielding material, 40 not shown, or reliance may be placed on accurate finishing of the two parts. At its rear end the barrel is reduced to provide an internal shoulder or stop 12 to limit the rearward movement of the piston, which in 45 assembling the parts is inserted through the forward end. The piston itself is equipped on its rear face with an eye 13 securely anchored in place, to which one end of a pliable or foldable actuating member is attached, in the present instance a small chain 50 14. The chain is preferably long enough to reach well outside of the barrel when the piston is fully advanced as in Fig. 2,

and its outer end is attached to a swivel 15 in the end of a cap 16 which may be 55 screwed on the reduced rear end of the barrel, as in Fig. 1.

To fill the barrel the cap 16 is removed and the piston is advanced as far as desired. This movement of the piston may 60 be accomplished by means of a lead pencil or any other device at hand, the user inserting it through the rear end of the barrel and with it pushing the piston in toward the nozzle 17 at the other end, to the 65 position shown in Fig. 2. Thrusting the nozzle in the ink the cap 16 is grasped with the fingers and drawn up steadily, thus retracting the piston which in turn sucks 70 ink into the barrel through the nozzle. 75 When the piston comes up to the stop or shoulder 12 the pen is held with the point up and the chain is coiled in the cap 16, whereupon the latter is screwed in place on the reduced end of the barrel, the swivel 15 permitting the cap or barrel to be rotated for the purpose without twisting the chain.

The cap 16 is preferably made as small as possible, consistent with convenience in 80 use and proper housing of the chain, and should permit the cap 18 to pass entirely over it so that in twisting the latter cap (18) to remove it the other will not be unscrewed. 85

It is to be understood that the invention is not limited to the specific details illustrated but can be embodied in other forms without departure from its spirit.

I claim—

In a self-filling fountain pen, an ink barrel, a piston movable axially therein, the rear end of the barrel being open to admit a suitable member for advancing the piston, a cap for closing the rear end of the barrel, and a chain of open links connecting the piston and cap and swiveled to one of said members and adapted to extend out of the rear end of the barrel for retracting the piston, said cap being removably mounted on the rear end of the barrel and adapted to house the chain when the piston is in retracted position. 100

In testimony whereof I hereto affix my signature.

CHARLES M. HAYNES,
